ABSTRACT

A tool for removing a peripheral band from a yieldable carton having an outwardly projecting non-planar area traversed by the band adjacent to an end of the carton in which the tool has a wedge end of substantial width with a lateral contour similar to the contour of this non-planar area, a fulcrum portion adjacent the end of the tool about which the tool is rockable and a handle attached to the wedge end for prying the band relative to the carton both in removing the band and applying the band to the carton once the wedge end of the tool has been inserted between the band and the carton.

BAND REMOVER FOR CARTONS

SUMMARY OF THE INVENTION

One of the features of this invention is to provide an improved tool for removing peripheral bands such as steel straps from a yieldable carton particularly of the tube and cap type in which the tool is insertable between the band and the carton and has a substantial width so that the tool may be rocked about the inserted end in removing the band from the carton and in reapplying the band or a similar band to the carton.

Other features and advantages of the invention will be apparent from the following description of one embodiment as illustrated in the accompanying drawings.

BRIEF DESCRIPTION OF THE DRAWINGS

FIG. 1 is an end elevational view of a tool embodying the invention.

FIG. 2 is a side elevational view of the tool.

FIG. 3 is a perspective view illustrating the operation of the tool in removing a band from a carton.

FIG. 4 is a view similar to FIG. 3 illustrating the applying of a metal band to the carton.

DESCRIPTION OF THE PREFERRED EMBODIMENT

As illustrated in the drawings the tool of this invention is particularly useful in removing and applying relatively non-stretchable bands such as the steel strap 10 to the end cap 11 of a tubular carton 12 which of course is a carton that is open at least one end but which is closed by a removable cap 11 to provide access thereto.

The carton 12 which in its assembled condition includes the cap 11 as well as the rectangular body 13 is constructed of a yieldable material such as rupture resistant corrugated paper-board. The band 10 traverses the corners 14 of the carton with these corners in their broadest sense being identified as outwardly projecting non-planar areas.

The tool 15 for removing and installing the peripheral band 10 on the carton comprises a wedge end 16 of substantial width having a lateral contour which in the illustrated embodiment is the horizontal section through the wedge end similar to the contour of the non-planar areas 14. Thus, in the illustrated embodiment each area 14 is a right angled corner so that the tool is constructed of two flat elongated plate members 17 and 18 arranged at a right angle to each other which of course is the contour of each corner 14.

Each elongated plate 17 and 18 has a pointed end 19 and 20 for aiding in inserting the wedge end between the carton 12 and specifically the end cap 11 thereof and the band 10 as illustrated in FIG. 4. The tool 15 also includes a curved handle 21 attached to the wedge end 16 for manipulating the tool in removing and installing the band 10.

The wedge end 16 of the tool is provided with a fulcrum surface about which the tool and the band 10 engaged therewith is rockable. Thus, in the illustrated embodiment each plate member 17 and 18 is curved in a smooth curvature as indicated at 22 and 23 in their separate ends 19 and 20. Thus, the ends 19 and 20 are curved rearwardly as illustrated in FIGS. 1 and 2 relative to the wedge end 16 of the tool.

In removing a band 10 from the carton 12 as illustrated in FIG. 2 the pointed and angled wedge end 16 of the tool is inserted between the band 10 and the end cap 11 with the angled side plates 17 and 18 of the tool resting flatly against the sides of the cap 11 from the corner 14 around which the tool extends. The operator 24 thereupon rocks the tool outwardly away from the body 13 of the carton and this is repeated in

easing the band 10 up over the top end 25 of the carton.

In reapplying the band to the carton the reverse procedure is followed, as illustrated in FIG. 4. Here the tool 15 is inverted with the wedge end 16 between the carton cap 11 and the band 10 and the tool is rocked back and forth about the curved ends 22 and 23 to work the band 10 back onto the carton and specifically the cap 11.

With this tool one operator can remove a non-elastic band such as a metal strap from a carton and reapply it for inspecting the contents of the carton or any other purpose. Ordinarily it takes two workmen to apply a band of this type.

The plates 17 and 18 forming the wedge end 16 of the tool can be readily formed by bending a single strip of metal or this wedge end can be formed by welding two separate plates 17 and 18 together at their edges of contact. This tool permits removing the band or bands over the corner of the carton where because of the non-planar area of the corner the carton is at its strongest. The carton, however, is yieldable to a sufficient degree to permit operation of the tool to remove and apply bands efficiently and by a single operator.

Having described my invention as related to the embodiment shown in the accompanying drawings, it is my intention that the invention be not limited by any of the details of description, unless otherwise specified, but rather be construed broadly within its spirit and scope as set out in the appended claims.

I claim:

1. A tool for removing and applying a peripheral band relative to a yieldable carton having an outwardly projecting non-planar area traversed by said band, said tool comprising: a thin, rigid wedge end defining an inner surface having a concave lateral contour complementary to the contour of said nonplanar area parallel to the longitudinal extent of the band; turned tip means on said wedge end for aiding the inserting of said end between the carton and band; and a handle attached to said wedge end oppositely of said tip means for prying said band relative to said carton both in removing said band and applying said band to the carton.
2. The tool of claim 1 wherein said turned tip means defines an arcuate fulcrum surface about which the tool and the band engaged therewith is rockable against said carton area.
3. The tool of claim 2 wherein said fulcrum surface is curved rearwardly with respect to the concavity of said wedge end.
4. The tool of claim 1 wherein said tip means is pointed to aid the inserting of the wedge end between the carton and the band.
5. The tool of claim 1 wherein said non-planar area of the carton defines a corner and said wedge end inner surface defines a complementary concave corner surface.
6. The tool of claim 5 wherein said wedge end comprises two planar end sections arranged at a preselected angle to each other with each tip means being curved rearwardly relative to the concavity defined by the planar end sections and pointed to aid in the inserting of the tool between the carton and the band and to provide a fulcrum surface around which the tool is manipulated by its handle in said prying of the band relative to the carton.
7. The tool of claim 1 wherein said handle is longitudinally arcuate.
8. The tool of claim 1 wherein said wedge end comprises a pair of similar right angularly related planar elements, and each said tip means comprises a V-shaped tip curved out of the plane of the associated element and disposed symmetrically to the longitudinal centerline of the element extending perpendicular to the longitudinal extent of the band.
